DUPLICATE BRIDGE PAD

Murtha K. Cline, Moscow, Idaho

Application January 16, 1951, Serial No. 206,276

3 Claims. (Cl. 273—151)

1

My invention relates to an improved duplicate bridge pad.

In the playing of the card game of contract bridge it is often desirable to have a number of groups of four players playing the same hands. The matter of arranging the cards and distributing them to the several tables where the players play presents quite a problem, particularly where the parties are relatively large such as in club or association competition.

It is the principal purpose of my invention to provide a novel pad or holder which can be utilized to secure the cards for each player in individual groups and thus be prefilled and laid on the tables at the beginning of each hand of play. The pads may be refilled with the next hand of play after the first hand is removed and while the play of the first hand is taking place. The pad is so arranged as to provide for easy marking to indicate the dealer and the relative positions of the players so that the matter of supplying the pre-arranged cards to the several tables is free of disorder and provides little opportunity for error.

More particularly it is a purpose of my invention to provide an improved card holding pad for the use of card players which lends itself readily to the pre-arrangement of the cards and the placing of the cards before the players.

The nature and advantages of the invention will appear more fully from the following description and the accompanying drawings wherein a preferred form of the invention is shown. The drawings and description are illustrative only, however, and are not intended to limit the invention except insofar as it is limited by the claims.

In the drawings:

Figure 1 is a plan view of an improved duplicate bridge pad;

Figure 2 is a sectional view taken on the line 2—2 of Figure 1; and

Figure 3 is a sectional view taken on the line 3—3 of Figure 1.

Referring now in detail to the drawings, my improved pad is made up of a suitable sheet material such as leather, Leatherette, sheet plastic composition or a suitable fabric. A square base sheet 5 forms the back of the pad. In order to provide a substantial thickness and relatively smooth edges, I prefer to form the sheet 5 with folded over top portions 6 along the four edges. These portions are cut out and sewed together at the corners on a diagonal line as indicated at 7 so that the edges such as 8 are covered. The base thus provided has a double thickness for

2

a substantial distance inward from its periphery and the bottom surface is an unbroken sheet. The next step in the production of the pad is to provide a smaller square covering sheet 10 of the same material. This sheet has its peripheral edge turned in a substantial distance and cut out at the corners so as to provide a peripheral portion of a double thickness and an intermediate portion of single thickness. Since the peripheral edge portion 11 of the sheet 10 is turned under, the edges where the corners are cut out do not need to be sewed together. The sheet 10 is placed on the sheet 5 and the two sheets are stitched together along the lines 12 and 13 and in addition the corner portions of the sheet 10 are stitched down to the sheet 5 by the stitching indicated at 14, 15 and 16. Then two rows of stitching 17 and 18 secure the sheets 5 and 10 together near the center. The resulting construction leaves four open pockets at 20, 21, 22 and 23, the sheet material being double at the edges of the pockets as indicated clearly in Figure 2.

The pockets 20 and 22 are relatively wide and shallow so that they may receive groups of cards 24 and 26 with the long edge of the cards parallel to the edge of the pad. The pockets 21 and 23 are somewhat deeper and not so wide so that they receive card groups 25 and 27 with the short edge of the card parallel to the edge of the pad. The pockets grip the cards with sufficient pressure to permit handling of the pad as it is filled with cards without the cards falling out. The doubled over portions 6 and 11 give extra rigidity to the pad and further the holding of the cards since they restrict the inlets to the pockets. Preferably the rows of stitching 12 and 13, and 17 and 18 are so spaced from the edges of the pad as to cause the cards when inserted in the pockets to project slightly beyond the peripheral edges of the base sheet 5 of the pad in order that they may be grasped and removed from the pad with ease.

It is evident that in preparation for playing of duplicate hands of bridge or other card games, the several decks of cards can be arranged in duplicate sets of four and each set of four can be placed in one of these pads in the same order throughout and when the pad is delivered to a table the cards will be in order to commence playing. For example, the pocket 20 may be marked as shown with the designation "dealer" and "W" for west position. The pocket 21 will carry "N" to indicate that it is for the north position and the pockets 22 and 23 marked "E" and "S" for east and south positions. The portions of the pad defined by the seams 14, 15 and 16 may be num-

bered to correspond to a table number. As soon as the cards are removed from a pad at a table, the pad may again be filled with another set of cards so as to be available for the next hand of play.

I have shown the pad as equipped with a back pocket 28 for holding the score pad that is commonly employed. This pocket is fastened at one edge 29 by the seam 12 while the opposite edge 30 is folded over and stitched as indicated at 31, the side edges of course being stitched to the sheet 5 to complete the pocket 28. This back 28, while useful, is not necessary and may be dispensed with.

It is believed to be evident from the foregoing description that I have provided a novel and convenient means for the pre-arrangement and handling of playing cards in groups for such games as duplicate bridge and the like. The detailed construction hereinbefore described is particularly effective for the purpose intended and in holding the cards in position in the pad. It is obvious, however, that various minor modifications may be made from the exact details shown and described without departing from the scope of the invention as defined in the following claims.

Having thus described my invention, I claim:

1. A pad for holding four groups of playing cards comprising a square base sheet of pliable material, a square top sheet of similar material substantially smaller in size, laid on the base sheet so that the side edges thereof are parallel to the side edges of the base sheet, the corner portions of the smaller sheet being secured to the larger sheet by securing a rectangular section of the smaller sheet to the larger sheet, each rectangular section being bordered on its two outer sides by the edges of the smaller sheet to provide four pockets facing outwardly for the insertion of four groups of cards.

2. A pad for holding four groups of playing cards comprising a square base sheet of pliable

material, a square top sheet of similar material substantially smaller in size, laid on the base sheet so that the side edges thereof are parallel to the side edges of the base sheet, the corner portions of the smaller sheet being secured to the larger sheet by securing a rectangular section of the smaller sheet to the larger sheet, each rectangular section being bordered on its two outer sides by the edges of the smaller sheet to provide four pockets facing outwardly for the insertion of four groups of cards, the outer portions of the top sheet being folded to provide a double thickness at each pocket mouth.

3. A pad for holding four groups of playing cards comprising a square base sheet of pliable material, a square top sheet of similar material substantially smaller in size, laid on the base sheet so that the side edges thereof are parallel to the side edges of the base sheet, the corner portions of the smaller sheet being secured to the larger sheet by securing a rectangular section of the smaller sheet to the larger sheet, each rectangular section being bordered on its two outer sides by the edges of the smaller sheet to provide four pockets facing outwardly for the insertion of four groups of cards, the lower sheet having peripheral edge portions folded inward upon the sheet and secured together at the corners to provide an edge portion of double thickness for the lower sheet beyond the periphery of the top sheet.
